UNITED STATES PATENT OFFICE.

ANDREW J. ALLARD, OF WASHINGTON, DISTRICT OF COLUMBIA, ASSIGNOR TO THE SALES CORPORATION, OF WASHINGTON, DISTRICT OF COLUMBIA, A CORPORATION OF VIRGINIA.

AUTOMATIC FLUID-OPERATED VALVE.

Application filed March 3, 1921. Serial No. 449,350.

To all whom it may concern:

Be it known that I, ANDREW J. ALLARD, a citizen of the United States, and resident of Washington, in the District of Columbia, 5 have invented certain new and useful Improvements in Automatic Fluid-Operated Valves, of which the following is a specification.

My invention relates to improvements in 10 automatic control mechanism for fluid pressure operated apparatus, and while particularly applicable to braking systems of vehicles and trains of vehicles, elevators, hoists, etc., it is capable of various other uses, as 15 for instance in heating and fuel supply systems etc., and as may depend upon any particular circumstances, its application may be either direct or indirect. Furthermore, the control of my improved mechanism may be 20 either mechanical, electrical, thermostatic or otherwise, since its fundamental principles of operation are susceptible to embodiment in mechanical structures of such varying design and within the scope of its beneficial 25 capabilities as otherwise will permit its control in still other manners.

More particularly my invention consists 30 of an automatic valve, which I will describe as associated with a well known type of fluid pressure train braking system, its purpose when so used being to cause an automatic application of the brakes whenever for any one of a number of different reasons the human factor in control of the train has failed 35 to do so when necessary, or whenever for various reasons the braking apparatus otherwise fails to function properly.

It is also my purpose to provide mechanism of the character mentioned which may 40 be associated with types of fluid pressure systems now in general use, without materially altering the same, and without affecting the ordinary mode of operation thereof.

My invention further resides in the provision 45 of mechanism of simple and comparatively inexpensive design to accomplish the functions aforementioned, either in a train braking system or in other fluid pressure operated apparatus. It is furthermore my 50 purpose to provide mechanism which is not only automatic in its initial operation, but which is also automatic in its return to normal position, following its controlling operation.

It is a further purpose to provide a mechanism of this character which is positive but which will also operate to control the apparatus with which it is associated without unnecessary harshness, as for instance in bringing a train to a smooth, quiet stop. 55 60

My purpose in describing my invention as associated with a train braking system is merely to describe one or the many uses and modes of operation to which its underlying principles are susceptible of application, but 65 the fact that I have chosen this manner of illustrating the use of my invention is not in any way to be inferred as an intention to restrict its range of possible utility.

In the drawings, wherein like characters 70 of reference denote corresponding parts in the different views:—

Fig. 1 is an elevation of a portion of a well known type of braking system showing 75 my improved valve operatively associated therewith;

Fig. 2, a vertical section through the valve showing its parts in their normal position; and

Fig. 3, a view similar to Fig. 2 showing 80 the position of the parts of the valve to cause an application of the brakes.

One type of train braking system with which my improved valve is adapted to be associated comprises a main fluid pressure 85 reservoir, an equalizing reservoir, an engineer's brake valve, and pipe connections between said reservoirs and said brake valve and with a train line to cause an application of the brakes in a well known 90 manner upon manipulation of the engineer's valve to exhaust air from the train line; release of the brakes being effected when the engineer's valve is manipulated to cause equal pressures upon either side of a piston 95 which controls the brake shoes, as is well known, and for which reason further illustration and description thereof is believed to be unnecessary, particularly since the only concern is in associating my valve with 100 the main reservoir, the engineer's brake valve and the train line in such manner that it will operate as desired.

For convenience in manufacture and assembly I have shown my improved valve 105 preferably composed of four main sections 14, 15, 16 and 17 adapted to be arranged, respectively, in superimposed relation with

the first section 14 serving as a closure for the lower end of section 15 and the top section 17 serving as a cap or closure for the upper end of section 16, said sections 5 14 and 17 being adapted for detachable association with sections 15 and 16, respectively, in any desired manner, as for instance, by means of screw threaded connections therewith, although said sections may 10 be flanged and bolted together if desired. The lower end of section 16 is designed to rest on the upper end of section 15, and these two sections are also adapted to be relatively detachably connected in any preferred manner as by means of bolts or other fasteners, 15 not illustrated.

At suitable points in the outer wall of section 15 are provided a pair of passages 18 and 19, respectively, which are preferably 20 though not necessarily diametrically oppositely disposed with respect to each other and which are preferably surrounded by screw threaded flanges or bosses formed on said section whereby pipes may be connected thereto for a purpose which will 25 later appear.

The upper portion of section 15 is formed into a cylinder 20 closed at its lower end with respect to either of the passages 18 30 or 19 by a horizontal partition 21. Likewise the lower end of said section 15 is closed throughout a major portion of its area by a horizontal partition 22 which denies communication between the passage 18 and any 35 part of section 14 except through a port 23 formed in said partition. Between the partitions 21 and 22 is a partition 24 having a port 25 formed therein providing a sole means of communication between the 40 passages 18 and 19. Passage 19, however, is at all times in communication with the interior of section 14, as illustrated.

Within the section 14 is a short cylinder 26 the lower end of which is open while 45 its upper end is closed by the lower face of partition 22 which it abuts in fluid tight engagement, and it is around the outside of this cylinder and the partition 22 that the passage 19 has communication with the 50 interior of section 14.

Carried within the section 14, below the cylinder 26 is a member 27 preferably cast integral with said section and having an opening 28 therein forming a guide for a 55 stem 29 projecting from the lower face of a piston 30 which is slidable in the cylinder 26. Towards the upper end of said member 27 the opening 28 is enlarged as shown at 31 thereby providing a space surrounding 60 the stem 29, which space extends to the upper end of said member and at its lower end communicates with an opening 32 leading to the atmosphere. The piston 30 is in the nature of a valve controlling communication 65 between the interior of section

14 and the atmosphere through openings 31 and 32. When the said piston is raised a flow of fluid through openings 31 and 32 is permitted, but when it is moved down a gasket carried thereby seats against the 70 upper edge of member 27 and thereby cuts off any flow of fluid through said openings. Extending through the piston 30 from top to bottom thereof is a small opening 33 the purpose of which will be fully explained 75 hereinafter.

Slidable in the cylinder 20 is a piston 34 and carried by this piston is a hollow stem 35 which projects through the partition 21 and below said partition carries a 80 valve 36 which cooperates with a seat surrounding the port 25 to close or open the same to thereby govern communication between passages 18 and 19 as may be determined by movements of said piston. 85

Also carried by said hollow stem at its lower end is a second valve 37 which cooperates with a seat surrounding the port 23 and is movable simultaneously with the first valve to control communication through 90 said last port, as is apparent. Near the partition 21 the side wall of cylinder 20 is provided with a small opening 38 which leads to the atmosphere.

Communication between the cylinder 20 95 and the interior of section 16 is denied except through a central tubular extension 39 rising from a wall 40 which closes the lower end of said section 16. Carried within said tubular extension is a member 41 having 100 an opening 42 therein which slidably receives the upper end of the stem 35. Communicating with the opening 42 is a passage 43 leading to the atmosphere, while another passage 44 communicates with the 105 interior of tubular extension 39 and also with passage 43 whereby said tubular member is also in communication with the atmosphere.

Formed in the upper portion of section 110 17 is a cylinder closed at its upper end and open at its lower end and which is stepped or shouldered to provide an upper portion 45 of any suitable diameter and a lower portion 46 having a diameter slightly 115 greater than the first portion. Arranged in this cylinder is a piston 47 which is also shouldered or stepped whereby it slidably fits both the larger and smaller bores of said cylinder. 120

Extending inward from the piston 47 is a stem 48 carrying at its lower end a ring 49 which is slidably fitted in the tubular extension 39 and, as controlled by movements of the piston, is adapted to cover or uncover the passage 44 to deny or permit communication between the tubular extension and the atmosphere. Also carried by the stem 48, between the tubular extension 39 and the piston 47, is an armature 50, of 125 130

such size and shape as to be disposed in operative relation to one or a plurality of electro-magnets 51 mounted within the section 16.

5 Like the piston 30 the armature 50 is in the nature of a valve controlling communication between the interior of the tubular extension 39 and the sections 16 and 17. When said armature is raised a flow of fluid 10 through the tubular extension is permitted, but when it is moved downward a gasket 52 carried thereby seats against the upper edge of the tubular extension and cuts off any flow of fluid therethrough. The section 15 16 is in constant communication with the opening 18 through a passage 53.

The constructions and relative arrangements of parts as set forth in the foregoing constitutes one form of my complete 20 automatic valve which, as shown in Fig. 1, is adapted to be interposed in the train line of types of fluid operated braking systems now in general use, whereby the purposes aforementioned are accomplished.

25 The train line pipe 54 connects in the usual manner with the engineer's valve 55 and is provided with a branch pipe 56 which connects with the lower end of section 14. A pipe 57 connects the engineer's valve with 30 opening 19 of my automatic valve, while another pipe 58 connects openings 18 with the main reservoir (not shown). The train line, to the side of the branch pipe 56 remote from the engineer's valve, is provided 35 with a normally open cock 59 which may be closed whereby the train line may be cut off from the engineer's valve and from my automatic valve when for any reason it is desired to do so, as for instance, when it 40 is desired to repair either valve. Furthermore, a pipe 60 connects pipes 57 and 58 and this pipe is provided with a normally closed cock 61 which may be opened in the event of malfunction of the automatic valve 45 to enable the fluid in the train line to be controlled in the ordinary manner by manipulation of the engineer's brake valve.

Positive and negative conductors 62 and 63, respectively, lead from the electro-magnets 51 to any suitable type of normally closed circuit breaking device or devices as conventionally illustrated at 64, and interposed in the circuit provided by these conductors is a suitable source of electric current such as the battery shown at 65. Any means for operating the device or devices 64 to break the circuit through the magnets 51 may be provided, one means for such purpose consisting of ramps placed at proper 50 intervals or at desired locations along the tracks and preferably operated in conjunction with semaphore or other signal devices so that they will be positioned to operate the devices 64 to break the circuit when the signal is in a position demanding an approach-

ing train to stop. In addition to the foregoing or equivalent means for breaking the circuit to thereby cause the automatic valve to operate it is apparent that other causes might accomplish the same purpose, as for 70 instance a broken conductor 62 or 63, a short circuit of said conductors or a weak battery.

When interposed in a train line as shown in Fig. 1 with the electric circuit closed and the magnets 51 energized the parts of the 75 valve will assume the position shown in Fig. 2, that is, the armature 50 is attracted by the magnets, the piston 47 is at the limit of its inward or downward movement, the upper end of the tubular extension 39 is 80 closed by the gasket 52, and the ring 49 is in uncovering relation to the passage 44. Therefore, since the upper surface of the piston is subject only to atmospheric pressure the main reservoir pressure reaching 85 the valve 36 by way of the pipe 58 raises, said valve establishing communication between the main reservoir and the engineer's brake valve, communication of the hollow stem 35 with the atmosphere being simultaneously cut off by reason of the upper end of said stem closing the inner end of passage 43. When the stem moves up it carries with it the valve 37 thus uncovering the port 23 and admitting pressure above 95 the piston 30, forcing the same downward and thus closing the exhaust port 31-32 from the brake pipe to the atmosphere.

The foregoing sets forth the normal position of the parts of my automatic valve, 100 and when in such position it is clear that the fluid in the train line may be controlled in an ordinary manner by manipulation of the engineer's valve. However, when for any reason the magnets 51 become deenergized, as, for instance, when the device 64 is operated by a ramp along the track to break the circuit through the conductors 62 and 63, the armature 50 is raised by the main reservoir pressure, present in the sections 16 and 17 by reason of the passage 53, acting upon the larger area of the bottom face of the piston 47, which pressure forces the piston upward and carries the armature with it, thus opening the upper end of the 110 tubular extension and admitting the main reservoir pressure above the large piston 34, forcing said piston downward until the valves 36 and 37 are seated and closing the ports 25 and 23, respectively, interrupting 115 communication between the main reservoir and the engineer's brake valve, and at the same time releasing the pressure above the piston 30 by way of the hollow stem 35 and passage 43. The train line pressure then 120 acting upon the under face of piston 30 moves same upward, uncovering the upper end of member 27 and permitting exhaust of the train line pressure through the openings 31-32, which exhaust or reduction of 125 130

the train line pressure will act to apply the brakes in a well known manner. When the magnets are again energized the armature is moved downward closing the upper 5 end of the tubular extension 39 and at the same time causing the ring 49 to uncover the vent 43, the pressure above the main piston 34 being thus cut off and vented, permitting the other parts of the valve to 10 return automatically to normal position in the manner previously set forth.

The opening 33 is in the nature of a bleed port permitting the escape of part of the train line pressure so that said valve will 15 not be moved to open the exhaust passages 31-32 too quickly so that the brakes will be applied with gradually increasing pressures to bring the train to a smooth, quiet stop.

The opening 38 is for the purpose of 20 avoiding a vacuum or compression of fluid by the piston 34, while an opening 66 in the piston 47, which may be referred to as a differential piston, is for the purpose of permitting equal pressure to both sides of said 25 piston.

While in the foregoing I have shown and 30 described a normally energized circuit for maintaining the parts of my mechanism inactive it is apparent that this arrangement might be readily reversed by providing a 35 normally deenergized circuit capable when energized of rendering the mechanism active. If this is done a spring or equivalent device will be provided to maintain the armature-valve normally closed. This is so clearly obvious as is also the possibility of 40 control by means of a thermostat by radio or otherwise that further illustration is believed unnecessary. In any event the manner 45 of control does not in any way effect the subsequent operation of the parts of my improved valve and therefore said control means may be varied at will.

Like the control means for the valve the 50 operation of the valve itself may be reversed to at predetermined times permit operation of the system or apparatus with which it is associated and at all other times prevent its operation. This may be done simply by 55 associating with the mechanism a normally deenergized control circuit instead of the normally energized circuit shown which will render the valve active normally and inactive when the circuit is energized.

Furthermore, in describing my invention 60 as associated with a train braking system I have referred to the fluid pressure pipe 54 as the "train line" pipe, but wherever this term is used it is to be construed to mean the equivalent fluid pressure pipe of any system with which my invention is used.

I claim:—

1. In a fluid pressure system, the combination with a fluid pressure pipe, a fluid pressure supply pipe, and a valve interposed in 65

one of said pipes and connected with the other and including parts maintained in predetermined normal relation by the fluid in said pipes and automatically operable by the same fluid to at predetermined times 70 effect reduction of pressure in said fluid pressure pipe without reducing pressure in said fluid pressure supply pipe.

2. In a fluid pressure system, the combination with a fluid pressure pipe, a fluid pressure supply pipe, and a valve interposed between said pipes and including parts maintained in predetermined normal relation by the fluid in said pipes to permit communication therethrough, and automatically operable by the same fluid to at predetermined times 75 effect a change in the pressure thereof and means for initiating operation of said valve.

3. In a fluid pressure system, the combination with a fluid pressure pipe and another pipe supplying fluid pressure to said first pipe, of a reciprocating valve interposed between said pipes and including parts movable solely under the influence of the pressure of fluid in said pipes, and operable to 80 at predetermined times effect a change of pressure in said fluid pressure pipe.

4. In a fluid pressure braking system, the combination with a fluid pressure pipe, and another pipe supplying fluid pressure to said first pipe, of a valve interposed between said pipes and including a normally closed exhaust port held closed by the pressure of fluid in said pipes and automatically opened 95 by the same fluid pressure at predetermined times to exhaust fluid from the fluid pressure pipe.

5. A fluid pressure control device including a reciprocating valve normally held in 100 position permitting communication through the device by the pressure of fluid which it controls.

6. A fluid pressure control device including a reciprocating valve normally held in 110 position permitting communication through the device by the pressure of fluid which it controls and movable under the influence of the same pressure to deny such communication.

7. In a fluid pressure system, the combination with a fluid pressure pipe, a fluid pressure supply pipe, and a valve interposed between said pipes and including electro-magnetic means operable to permit the parts of 120 said valve to be automatically actuated by the pressure of fluid in said pipes to effect a change of pressure in said fluid pressure pipe.

8. In a fluid pressure system, the combination with a fluid pressure pipe, a fluid pressure supply pipe, a valve interposed in one of said pipes and connected with the other and including means operable solely by the pressure of fluid in said pipes to permit and 125

deny communication through said fluid pressure pipe, and means to control the operation of said first named means.

9. A valve adapted to be interposed in the fluid pressure supply pipe and connected with the train line pipe of a fluid pressure breaking system for automatically controlling the pressure of the fluid in said system, including a port permitting communication through said valve, closing means for said port maintained normally in port opening position by the pressure of the fluid in said pipes, said valve also including a vent, vent closing means normally maintained closed by the pressure of the fluid in said pipes, and means operable to permit said port closing means and said vent closing means to move under the influence of the pressure in said pipes to respectively close said port and open said vent, whereby a change of pressure in said train line is effected.

10. A valve adapted to be interposed in the fluid pressure supply pipe and connected with the train line pipe of a fluid pressure braking system for automatically exhausting fluid from the train line pipe, including a port, means normally held under the influence of the pressure in one of said pipes in a port closing position, and means operable at predetermined times to permit the pressure in the train line pipe to move said closing means to open said port for the purpose set forth.

11. A valve adapted to be interposed in the fluid pressure supply pipe and connected with the train line pipe of a fluid pressure braking system for automatically exhausting fluid from the train line pipe, including a port permitting communication through said valve, means for closing said port maintained normally inactive under the influence of the pressure in one of said pipes, and means at predetermined times to permit exhaust of fluid from said train pipe, and permit said closing means operable to move under the influence of said pressure to close said port.

12. A valve adapted to be interposed in the fluid pressure supply pipe and connected with the train line pipe of a fluid pressure braking system for automatically exhausting fluid from the train line pipe, including a normally open passage through said valve, maintained open by the pressure of the fluid in said pipes, a normally closed vent through which fluid may be exhausted from the train pipe, said vent being maintained closed by the pressure of the fluid in said pipes, and means operable under the influence of the pressure in said pipes to at predetermined times close said passage and simultaneously open said vent.

13. A valve adapted to be interposed in the fluid pressure supply pipe and connected with the train line pipe of a fluid pressure

braking system for automatically exhausting fluid from the train line pipe, including a normally open passage between the fluid pressure supply pipe and the usual manually operated valve for controlling the flow of fluid in said pipes, a member for closing said passage movable to both active and inactive positions by the pressure of fluid in said supply pipe, and means operable at predetermined times to permit exhaust of fluid from said train pipe and cause said pressure to act to move said member to close said passage.

14. A valve adapted to be interposed in the fluid pressure supply pipe and connected with the train line pipe of a fluid pressure braking system for automatically exhausting fluid from the train pipe, including a normally open passage between the fluid pressure supply pipe and the usual manually operated valve for controlling the flow of fluid in said pipes, a member for closing said passage including a hollow stem, a vent, means normally held in a position closing said vent under the influence of the pressure in said passage and means operable at predetermined times to cause the pressure to act to move said member to close said passage, the closing pressure upon said vent closing means being relieved through said hollow stem whereby said closing means is moved under the influence of the pressure in the train pipe to open said vent.

15. A valve adapted to be interposed in fluid pressure braking system for automatically exhausting fluid from the train line of said system, including a movable element, means normally holding said element at the limit of its movement in one direction whereby the parts of said valve are maintained in position permitting control of the fluid by the usual manually operated valve forming a part of said system, and a differential piston operatively associated with said member and movable under the influence of the pressure in said system when said holding means becomes inactive, to cause other parts of said valve to move under the influence of said pressure to deny control of the system to said manually operated valve and exhaust fluid from the train line.

16. A valve adapted to be interposed in a fluid pressure braking system for automatically controlling the fluid in said system, including a movable element, electro-magnetic means including a circuit and a circuit making and breaking device for holding said element normally in a position whereby the parts of said valve are maintained in position permitting control of the fluid in said system by means other than said valve, a differential piston operatively associated with said element and movable under the influence of the pressure in said system, upon operation of said circuit making and

6
breaking device, to move said element to permit other parts of the valve to operate to deny control of the system to said manually operated valve and effect a change of 5 pressure in said train line pipe.

17. A valve adapted to be interposed in a fluid pressure braking system for automatically exhausting fluid from the train line of said system, including an element normally held in a position permitting communication through said valve, a piston connected to said element and movable under the influence of the pressure in said system to move said element to deny said communication, means normally denying access of 10 said pressure to said piston, means for actuating said last named means, and means operable upon movement of said member to cut off said communication to effect a change 15 of pressure in said train line.

18. A valve adapted to be interposed in a fluid pressure system, for automatically controlling the same, including means held under the influence of the pressure in said system in a position maintaining constant pressure in said system, and means operable at predetermined times to permit the fluid to move said piston and actuate said first means to effect a change of pressure in said 20 system, said first named means being operable to effect a gradual change of pressure as set forth.

19. A valve adapted to be interposed in the fluid pressure supply pipe and connected 25 with the train line pipe of a fluid pressure braking system for automatically controlling the same, including a plurality of relatively detachable sections, one of said sections having a port therein permitting communication through said valve, an element 30 for closing said port including a hollow stem, a vent, a member for closing said vent, a second port permitting access of fluid to said member, a second element associated with 35 said hollow stem and movable in unison with said first element for closing said second port, the closing pressure upon said member being exhausted through said hollow stem 40 when the elements are closed, a piston on 45 said stem operable by said pressure to move 50

said elements to closing position, means normally denying access of pressure to said piston, and a differential piston operable to move said last named means to permit access of pressure to said last mentioned piston to 55 permit said member to be moved to uncover said vent, substantially as set forth.

20. In a fluid pressure system, the combination with a fluid pressure pipe, a fluid pressure supply pipe, and a valve interposed in one of said pipes and connected with the other and including parts automatically operable by the fluid in said pipes to a predetermined times effect a gradual reduction of pressure in said fluid pressure pipe without reducing pressure in said fluid pressure supply pipe.

21. A fluid pressure control device including a casing, a reciprocating valve contained within said casing for controlling 70 communication therethrough, and reciprocating parts also contained within the casing for controlling movements of said reciprocating valve, said valve and parts being normally held in position permitting communication through the casing by the pressure of fluid controlled by said device.

22. In a fluid pressure system the combination of a pressure pipe, a supply pipe, and a valve automatically operable by the fluid in 80 said pipes with an external means for inaugurating movement of the valve parts and their return to normal position by the fluid contained in said pipes.

23. A fluid pressure control device including a reciprocating valve normally held in position permitting communication through the device by the pressure of fluid which it controls, and external means for initiating closing movement of said parts.

24. A fluid pressure control device including a port providing communication therethrough, and a reciprocating valve movable under the influence of the pressure of the fluid controlled by said device to both 95 close and open said port.

In testimony whereof I hereunto affix my signature.

ANDREW J. ALLARD.
